UNITED STATES PATENT OFFICE.

LOUIS W. AUSTIN, OF WASHINGTON, DISTRICT OF COLUMBIA.

ELECTRICAL CIRCUITS.

Application filed January 19, 1924. Serial No. 687,281.

My invention relates generally to electrical circuits, and particularly to those in which high frequency electrical currents are produced of the order of frequency commonly used in radio communication, the particular object of my invention being to produce high frequency electrical currents and maintain the frequency constant.

My invention is of particular value in receiving high frequency electrical currents by the heterodyne or beats methods, and is most effective in receiving such signals in the higher range of frequencies, for instance, 1000 kilo-cycles (300 meter wave length).

It is well known that in the use of a three-electrode vacuum tube oscillator having coupled grid and plate circuits to produce oscillations, the period of the oscillations being set by the period of one or the other of these circuits, that variations in the filament temperature or variations in the plate circuit energy supply potential will cause variations in the frequency of the oscillations, and these variations become particularly noticeable in receiving by heterodyne at the higher frequency where a slight change in the frequency of a locally generated oscillation produces a substantial change in the frequency of the beat oscillations, or may even cause the beat oscillations to vary beyond the range of audibility.

It is the principal purpose of my invention to prevent variations within the vacuum tube from materially influencing the constants of the circuit determining the period of the oscillations of the system.

My invention will be best understood by reference to the accompanying drawing in which A represents a conventional type of antenna coupled to a secondary oscillatory circuit containing inductances L_2 and L_3 and capacity C_1 , the coupling being had with the antenna inductance L_1 . This oscillatory circuit is connected to the grid G and filament F of the vacuum tube VT through a very small capacity C_2 , and may include a serially included resistance R_2 . R_3 is a resistance of the order of megohms in shunt to the capacity C_2 , ordinarily termed a grid leak. The vacuum tube VT also has a plate circuit including inductance L_4 , telephones T and battery B_2 . Condenser C_3 is the usual radio frequency by-pass around the high impedance telephones T. The grid and plate circuits are interlinked, through

the coupling between the inductance L_3 and inductance L_4 . Battery B_1 provides for heating the filament F, and rheostat R_1 permits of varying the amount of filament current. The connection of the filament terminal of the plate circuit to the battery B_2 is shown as variable, to permit of varying the plate potential.

It has been the practice heretofore to provide a condenser in the position of my condenser C_2 shunted by a grid leak R_3 in circuit arrangements such as I have illustrated and described, but the prior practice has never made this condenser of sufficiently low capacity to effectively prevent variations in the vacuum tube from materially affecting the period of the oscillatory circuit L_2 , L_3 , and C_1 . Ordinarily if the conditions in the tube vary so as to alter the impedance of the internal path between the grid G and the filament F, these variations acting in shunt with the condenser C_1 cause variations in the period of the oscillations. By making the capacity of C_2 sufficiently small so that the capacity reaction in this condenser is the controlling reaction in the circuit produced by the connections of the oscillatory circuit to the grid and filament of the vacuum tube, the variations in the tube will not cause substantial variations in the period of the oscillatory circuit.

I have also found that in some cases the control of the constancy of the generated frequency is improved by inserting a resistance R_2 of several hundred ohms. It is common practice to use a grid condenser in the location shown by my condenser C_2 of 250 micro-microfarads and above, and I have found that by reducing this capacity to the order of 25 micro-microfarads I have been able to generate oscillations of the order of 1000 kilo-cycles, and use these oscillations for the reception of sustained wave signals by the heterodyne method without any noticeable change in frequency under varied conditions in the vacuum tube.

In fact I prefer to employ a tight fixed coupling between inductances L_2 and L_4 , and vary the strength of the oscillations by varying the temperature of the filament F through the rheostat R_1 , or by varying the plate circuit potential through varying the potential of the battery B_2 .

While I have illustrated and described my invention in connection with the reception of radio signals, it is of course not so limited as

there may be many other uses for a generator of constant frequency high frequency oscillations.

Having described my invention I claim:

- 5 In a regenerative receiving circuit including a vacuum tube detector, a grid-filament circuit and a plate-filament circuit including a regenerative inductance, the combination in the grid-filament circuit of a secondary inductance, a second inductance in series

therewith and coupled to the regenerative inductance in the plate-filament circuit, a tuning condenser in parallel with the secondary inductance and the second inductance forming an oscillatory circuit therewith, a 15 grid-condenser and grid-leak in series with the oscillatory circuit in the grid-filament circuit and a resistance in series with the oscillatory circuit and the grid-condenser.

LOUIS W. AUSTIN.
